UNITED STATES PATENT OFFICE

104,833

DESIGN FOR A WRAPPING PAPER OR SIMILAR ARTICLE

Elsie J. Das, Honolulu, Territory of Hawaii, assignor to Watumull Brothers, a firm composed of Jhamandas Watumull, Gobindram J. Watumull and Ramchand Watumull and doing business as East India Store, Honolulu, Territory of Hawaii

Application January 4, 1937, Serial No. 66,881

Term of patent 3½ years

To all whom it may concern:

Be it known that I, Elsie J. Das, a citizen of the United States, residing at Honolulu, in the county of Honolulu, Territory of Hawaii, have invented a new, original, and ornamental Design for a Wrapping Paper or Similar Article, of which the following is a specification, reference being had to the accompanying drawing, forming part thereof.

In the accompanying drawing:—

The figure is a face view of a wrapping paper, showing my new design.

The design is applicable to other articles of analogous nature.

I claim:

The ornamental design for a wrapping paper or similar article, substantially as shown and described.

ELsie J. Das.
